UNITED STATES PATENT OFFICE

2,197,925

CHECK MECHANISM

Ernest Davis, Syracuse, N. Y., assignor to The Prosperity Company, Inc., Syracuse, N. Y., a corporation of New York

Application September 10, 1937, Serial No. 163,286

6 Claims. (Cl. 188—93)

This invention relates to checks or check mechanisms, particularly for machines having an opening and a closing movement, for checking or absorbing shocks, as the machine approaches the end of its closing movement and as it approaches the end of its opening movement, and has for its general object a checking mechanism of the vane type involving a reversely movable piston member or vane having means for adjusting the checking effect, and if desirable, a different checking effect at the end of one movement of the machine, as for instance, the closing movement than at the end of its other movement, as the opening movement.

It also has for its object a particularly simple and compact construction of a hydraulic checking device.

Other objects appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a front elevation, with a section of the front cover broken away, of a checking device embodying this invention.

Figure 2 is a side elevation looking to the left in Figure 1.

Figure 3 is a front elevation, with the cover of the casing and the cover of the pressure chamber removed.

Figure 4 is a sectional view taken approximately on line 4—4, Figure 3.

Figure 5 is a sectional view taken on line 5—5, Figure 4.

Figures 6 and 7 are views similar to Figures 3 and 4 illustrating modified form of the adjusting member.

This check mechanism comprises, generally, a casing formed with a reservoir for a hydraulic liquid, a piston chamber located to receive the liquid from the reservoir and to discharge thereinto, a piston member or vane having a back and forth movement, and preferably an oscillating movement in the piston chamber, the chamber having outlets into the reservoir through which the liquid is passed under the action of the piston or vane, and means to adjust the outlets to vary the checking effect. In Figures 3 and 4, the outlets are arranged to be passed by the piston or vane in its movement, during the end periods of its stroke, and the adjusting means

operable to close one or more of a series of outlets to vary the checking action.

The checking mechanism shown in Figures 3 and 4 comprises two series of outlets arranged on opposite sides of the position occupied by the piston or vane, when in the central or intermediate period of its stroke, together with means individual to each series for closing or cutting out one or more of the outlets of each series.

The check mechanism also comprises an intermediate port operating to reduce the resistance on the vane, as the checked machine is passing through the intermediate part of its opening and closing movements.

1 designates the casing formed with an oil reservoir 2. 3 designates a piston chamber located in the oil reservoir 2, the piston chamber being here shown as cylindrical and arranged with its axis coincident with the axis of the reservoir, which is also cylindrical, the piston chamber being spaced apart from the cylindrical wall forming an annular oil passage. The casing is also formed with an upper portion 6 forming a gear box 7. The front wall of the casing is a removable cover, this cover being secured in position, as by screws 10. The end of the piston chamber 3 opposed to the cover is closed by a plate 11 which is spaced from the cover and is secured in position, as by screws 12. The space closed by the casing cover is a gear box.

13 designates a piston member, this being shown as an oscillating piston, vane or blade, mounted on a shaft 14 journalled at one end at 15 in the rear wall of the reservoir 2, this shaft 14 extending through the plate 11 and being journalled at its front end in a cup or closed bearing 16 in the cover 9.

17 is a gear fixed or keyed on a shaft 18 journalled in the upper portion 6 of the casing 1 and inside the casing. 20 is a gear meshing with the gear 17 and mounted and pinned on the shaft 14 adjacent to the cover. 21 is a rock arm mounted on the outer end of the shaft 18, this being designed to be connected to a moving part of a machine having an opening and a closing movement, as the actuating mechanism for the head-carrying or yoke lever of a garment or laundry press.

During the closing movement of the machine, the piston moves from the full line position, shown in Figure 3, into the dotted line position, and during the opening movement of the machine, from the dotted line position to the full line position.

The casing 1 is filled with oil to a level L above

the piston chamber 3 through a suitable filler opening 22, which is normally closed by a closure or plug 23. The piston chamber communicates with the reservoir or the lower portion of the casing through a port 24 and also through outlets to be presently described. The port 24 is located in the lower portion of the piston chamber and arranged to be passed by the piston when the piston is passing through the intermediate period of its stroke, from the full line position (Figure 3) to the dotted line position, and vice versa. The port 24 is provided with tapering walls 24a at the ends thereof with respect to the direction of movement of the piston vane to avoid a sudden checking effect, as the piston vane is passing the port 24 in either direction.

The piston chamber 3 is provided with a suitable partition or abutment 25 located diametrically opposite the port 24.

26 and 27 (Figures 3 and 4) designate two series of outlet ports extending through the rear wall of the piston chamber 3 and opening into the casing through passages or bores 28, 29 in the rear end wall of the piston chamber, one series, as 26, serving to control the outlet of the oil during the end of the closing movement of the machine to which the device is connected, and while the piston is moving toward the end of its stroke in one direction, and the other series 27 serving to check the flow of oil under the action of the piston during the end of the stroke of the piston in the opposite direction, during the opening movement of the machine. The outlets of each series 26, 27 are so arranged that they are passed progressively by the piston in its movement in one direction or the other.

The means for varying the checking effect operates to open or close one or more of the ports 26, 27 of each series, there being one adjusting means for each series. The adjusting means consists of a movable plunger or valve 30 or 31 mounted in the passage or bore 28 or 29 and adjustable progressively across the ports 26, 27, each valve 30, 31 having a suitable stem 32 or 33 having a knob or handle 34 or 35 at its outer end. It is held in adjusted position by suitable set nuts 36, 37. Obviously, by moving the plunger or valve 30 or 31 outwardly to its full extent, all the ports 26 or 27 will be opened and by moving it inwardly, one or more of the ports 26 or 27 will be closed. Also, the valves or plungers 30, 31 may be adjusted to give a different checking effect, if desired, during the closing movement of the machine from that during the opening movement.

The casing 1 is secured to the frame F of the machine to which the checking device is applied in any suitable manner, as by screws 40, 41.

In operation, during the closing of the machine to which the checking mechanism is applied, the shaft 18 is actuated by the arm 21 and the motion thereof transmitted by the gears 17, 20 to the shaft 14 and the piston member 13, moving the piston member from the full line position (Figure 3) to the dotted line position. During the first half of this movement, the oil is pressed in front of the piston out through the port 24 with very little resistance. After the piston 13 passes the port 24, the only outlet for the oil is through the ports 26. As these ports are passed, one by one, the resistance, and hence the checking effect, gradually increases. The amount of resistance may be regulated by adjusting the valve 30. The oil on the advance side 75 of the piston, with respect to the direction of

movement, is compressed against the abutment 25, and hence is forced out through the ports 26 or 27. During the opening of the machine, the piston is actuated by the arm 21 through gears 17 and 20 in the reverse direction from the dotted line position (Figure 3) toward the full line position, and the oil first passes freely out through the port 24, until the piston passes the port 24, when the checking effect is controlled by the ports 27. The oil displaced by the piston 13 through the port 24 flows in behind the piston through the port 24, after the port has been passed by the piston.

In Figures 6 and 7, the means for varying the checking effect comprises valves 50, 51 communicating with the opposite ends of the piston chamber 3 and adjustable from the outside of the casing 1. The valves are shown as spring-pressed balls, each located in a cage 52 detachably mounted in the rear wall of the piston chamber 3 through a work hole 53 in the rear wall of the casing 1. Each ball is held off its seat 54 by a member, as a screw 55, threading through a plug 56 closing the work hole. The screw is operable to locate the ball or valve various distances off its seat and thus vary the checking effect. Obviously, the balls may be adjusted differently to effect a different checking effect during the closing of the machine from during the opening. The operation of the machine is the same as that described, with the exception that the checking effect is not varied by the piston vane passing the outlets successively.

Owing to the construction of the casing with the piston chamber submerged in the oil reservoir and the shaft 14 mounted in the cup bearing in the cover 9, and the shaft 18 located out of the oil reservoir, and hence out of the pressure area of the piston member, the oil can not leak out of the casing along shafts and through bearings.

What I claim is:

1. In a hydraulic check mechanism, a casing formed with a reservoir for a checking liquid, a piston chamber located to receive the liquid from the reservoir, a piston having a back and forth movement in the chamber, the chamber having a port opening into the reservoir midway between the positions occupied by the piston, when at the ends of its throw, and located to be passed by the piston, the chamber also having a series of outlets into the reservoir on opposite sides of said port, the outlets of each series being arranged progressively with respect to the movement of the piston, means operable at will to open and close the outlets of each series more or less, and thereby vary the progressive checking effect, and means for connection to a moving part for actuating the piston.

2. In a hydraulic check mechanism, a casing formed with a reservoir, a cylindrical piston chamber located to receive liquid from the reservoir, an oscillating piston working in the piston chamber and mounted on an axis coaxially with the axis of the piston chamber, the piston chamber having a port opening into the reservoir and located midway between the ends of the throw of the piston, and arranged to be passed by the piston, the piston chamber having a series of outlets into the reservoir on opposite sides of said port, means common to each series of outlets for closing the ports of the series successively and thereby varying the checking effect, and means for connection to a moving part for actuating the piston.

3. In a check for machines having an opening and a closing movement, a casing formed with a cylindrical reservoir for a checking liquid, a cylindrical piston chamber located in the reservoir and spaced apart from the cylindrical wall thereof, a piston having an oscillating movement mounted in the chamber on an axis coaxial with said chamber, the chamber having two series of outlets opening through an end wall thereof into the reservoir and located on opposite sides of the piston when in the intermediate period of its throw, the piston chamber also having a port opening into the reservoir and located to be passed by the piston when in the intermediate period of its movement and between said two series of outlets, an abutment located in the portion of the piston chamber diametrically opposite said port, and means for connection to a moving part of the machine for actuating the piston.
- 20 4. In a check mechanism, a casing formed with a reservoir for a checking liquid, a piston chamber located to receive the liquid from the reservoir, a piston having a back and forth movement in the chamber, the chamber having a port opening into the reservoir midway between the positions occupied by the piston when at the ends of its throw and located to be passed by the piston, the chamber also having outlets into the reservoir on opposite sides of said port and opening into the chamber along lines extending in opposite directions away from said port with respect to the movement of the piston to effect a progressive checking, and means operable at will to open and close the outlets more or less to vary the progressive checking effect.
- 25 5. In a hydraulic check mechanism, a casing formed with a cylindrical reservoir for a checking liquid, a cylindrical piston chamber located
- in the reservoir and spaced from the cylindrical wall thereof, a piston having an oscillating movement mounted in the chamber on an axis coaxial with said chamber, the chamber having a port opening into the reservoir and located to be passed by the piston when in the intermediate period of its movement, the chamber being also formed with outlets in the portion thereof on opposite sides of said port, the outlets opening into the chamber along lines extending in the directions of movement of the piston away from said port in opposite directions to effect progressive checking, an abutment located in the portion of the chamber diametrically opposite the port, and means for effecting relative rotary movement of the piston and the casing.
- 10 6. In a hydraulic check mechanism, a casing formed with a cylindrical reservoir for a checking liquid, a cylindrical piston chamber located in the reservoir and spaced from the cylindrical wall thereof, a piston having an oscillating movement mounted in the chamber on an axis coaxial with said chamber, the chamber having a port opening into the reservoir and located to be passed by the piston when in the intermediate period of its movement, the chamber being also formed with outlets in the portion thereof on opposite sides of said port, the outlets opening into the chamber along lines extending in the directions of movement of the piston away from said port in opposite directions to effect progressive checking, an abutment located in the portion of the chamber diametrically opposite the port, and means for effecting relative rotary movement of the piston and the casing.
- 15 20 25 30 35

ERNEST DAVIS.
